COLLAPSIBLE TUBE CLOSURE

Martin Tierman, Blawnox, Pa.

Application April 19, 1932, Serial No. 606,218.

4 Claims. (Cl. 221—60)

This invention relates to collapsible tubes and its general object is to provide a tube for pastes, creams, ointments and the like with valve means that is normally held closed and is automatically opened by the contents of the tube when pressure is applied to the latter for dispensing the contents therefrom, but when the pressure is relieved the valve is automatically closed, with the result the contents are kept normally sealed and therefore free from contamination.

A further object of the invention is to provide a collapsible tube with valve means of the character set forth, that is extremely simple in construction, inexpensive to manufacture, and efficient in operation and service.

This invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in which:—

Figure 1 is a fragmentary vertical sectional view showing the valve in closed position.

Figure 2 is a similar view with the valve in open position.

Figure 3 is a sectional view taken approximately on line 3—3 of Figure 1.

Figure 4 is a sectional view taken approximately on line 4—4 of Figure 3.

Figure 5 is a sectional view taken approximately on line 5—5 of Figure 3.

Referring to the drawing in detail, the reference numeral 1 indicates a body of a collapsible tube which has formed therewith and rising therefrom a neck 2, the latter being provided with a closed top 3 and a slot 4 arranged in the circumferential wall thereof as best shown in Figures 1 and 2. The slot 4 is the outlet for the contents of the tube and is preferably rectangular in shape so that the contents will be dispensed in ribbon formation as will be apparent, but of course it can be of any shape without departing from the spirit of the invention.

Mounted for slidable movement on the neck 2 is a cap 5 that snugly receives the neck and has secured thereto through the instrumentality of pins 6 a strip 7 that bridges the neck, and it will be noted that the pins 6 are formed with the strip 7 and are mounted for reciprocation in diametrically opposed vertical slots 8 formed in the neck 2 as clearly shown in Figure 3.

Secured to the strip 7 is a disk 9 which constitutes the valve core of my device and while this disk may be formed from any appropriate material it is preferably made from cork. The strip 7 not only acts as a carrying means for the disk 9 but also has an abutment for the lower convolution of a coil spring 10, while the upper convolution of the spring is arranged in contacting engagement with the top 3.

The coil spring retains the cap 5 and disk 9 in a position to cover the slot 4 as shown in Figure 1, but when pressure is applied to the tube, it will be obvious that the contents of the tube will force the disk against the coil spring 10 to uncover the slot 4, which will of course result in the contents of the tube being dispensed through the slot as shown in Figure 2. However, when the pressure is relieved from the tube, the coil spring will dispose the disk and cap to normal position for closing the slot, and as the cap closes the outside of the slot, the portion of the contents of the tube in the slot, as well as the remaining contents in the tube is kept free from contamination and therefore in a clean and sanitary condition.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. In a collapsible tube, dispensing means therefor and including a neck having an outlet and a closed top, a disk mounted for slidable movement in said neck and normally closing the outlet, a cap surrounding the neck and mounted for movement thereon, said cap normally closing the outlet, means connecting the cap with the disk for movement in unison, spring means for the disk and abutting the top to urge the disk and cap to normal closed position, and said disk and cap being moved to a position to uncover the outlet, by the contents of the tube bearing against the disk when pressure is applied to the tube.

2. In a collapsible tube, means for dispensing the contents thereof and including a neck provided with an outlet arranged in the circumferential wall thereof, a cap mounted for slidable movement on the neck, a disk mounted for slid- able movement within the neck, a strip secured to the disk, means formed with the strip and

- fixed to the cap whereby the cap and disk move in unison, a coil spring having its end convolutions engaging the strip and the top of the neck respectively to normally hold and urge the disk 5 and cap to a position to cover the outlet, and said disk being moved to a position by the contents of the tube when pressure is applied to the latter to cause the disk and cap to uncover the outlet for the passage of the contents therethrough.
- 10 3. A tube of the class described, having a neck portion with an outlet formed therein, and a lid integrally attached to and closing the mouth of the said tube, a plunger mounted within the said neck portion and being provided at its bottom with a disc of suitable material, a collar mounted outside upon the said neck portion, a cross-bar integrally attached to the said plunger and collar, the wall of the said neck portion being formed with oppositely disposed oblong openings to permit vertical movement of the said
- 15 cross-bar and incidental opening and closing of the said outlet by means of the said plunger and collar, respectively, and a spring mounted between the said lid and cross-bar.
4. In a tube of the class described, a neck portion closed at its top and formed with a discharge opening upon its side, a cross-bar mounted in the said neck portion, a spring arranged between the said closed top and the cross-bar, and actuating the latter, a plunger attached to the said cross-bar inside the neck portion, and a collar secured to the said cross-bar upon the outside of the said neck portion, the latter being formed with vertical slots to permit up and downward movement of the said cross-bar, the 80 said plunger and collar being adapted to operate with the discharge opening of the said neck portion.
